UNITED STATES PATENT OFFICE.

JAMES K. ROBINSON, OF LITTLE ROCK, ARKANSAS.

VENTILATOR.

1,076,451.

Specification of Letters Patent. Patented Oct. 21, 1913.

Application filed April 1, 1913. Serial No. 758,130.

To all whom it may concern:

Be it known that I, JAMES K. ROBINSON, a citizen of the United States, and a resident of Little Rock, in the county of Pulaski and 5 State of Arkansas, have made certain new and useful Improvements in Ventilators, of which the following is a specification.

My invention relates to ventilators, and particularly to ventilators of the type used 10 within and upon buildings for the purpose of maintaining circulation of air in attics, rooms, halls and other parts of the edifice. My ventilator may be also employed in connection with the discharge of smoke, gases 15 and vapors from buildings, and also from analogous structures.

More particularly stated my invention comprehends a ventilator provided with a stationary draft member such as pipe, flue, 20 or chimney, and a cowl journaled upon said member and provided with means for shifting the cowl under control of the wind into different angular positions, the cowl being provided with means for facilitating the 25 travel of air through the draft member, thus forcing a draft within the latter.

My invention further relates to improved mechanism for enabling air currents or transient winds to produce or increase, by aspiration, forced drafts within the draft member, and for making such drafts relatively strong in proportion to the strength of the wind controlling them.

My invention further contemplates various improvements in the construction of 35 ventilators for the purpose of increasing the general efficiency thereof.

Reference is made to the accompanying drawing forming a part of this specification, 40 and in which like letters indicate like parts.

Figure 1 is a substantially central vertical section through my improved ventilator. Fig. 2 is an elevation of the same. Fig. 3 is a section substantially on the broken line 45 3-3 of Fig. 1 looking in the direction of the arrow. Fig. 4 is a detail showing in perspective the upper portion of the draft member and parts carried thereby.

A funnel 5, adapted to extend upwardly or outwardly from the portion of the building to be ventilated, carries a cylinder 6, these parts together constituting a draft pipe or draft member. Mounted upon the cylinder 6 is a flange 7 of substantially frusto-conical 55 form. An arch 8, made preferably of strap metal and having the form indicated in

Figs. 1 and 4, is mounted upon the upper end of the cylinder 6 and extends upwardly therefrom. A bridge 9, made also preferably of strap metal, extends diametrically 60 across the cylinder 6, and is at its ends connected with said cylinder and with the adjacent ends of the arch 8. The bridge 9 is provided with a hole 9^a, as will be understood from Fig. 4. The bridge 9 carries a 65 stirrup 10 secured rigidly to its underside. The arch 8 is provided with a hole 11 which is in alinement with the hole 9^a, as will be understood from Fig. 4.

A cowl 12 carries two fins 13 secured rigidly within it and extending outwardly, as will be understood from Figs. 1 and 3. These fins diverge from each other and are displaced angularly in relation to each other by 95 to 120 degrees. 75

A supporting stem 14 is provided with a shaft portion 15 which extends through the holes 11, 9^a, and rests upon the stirrup 10. The stem 14 is further provided with a leaf portion 16 which is secured to the cowl 12 80 at the top thereof, as indicated in Fig. 1.

A vane 17 is mounted upon the cowl and is of suitable form to enable the cowl to be shifted by the wind. The cowl 12 at its lower end is provided with a flange 18 85 which is of substantially frusto-conical form. A pin 19 extends through the shaft portion 15 and supports a washer 20, the latter encircling the shaft portion 15 and being located just below the top of the arch 8. 90

When the parts are in position, as indicated in Figs. 1 and 2, the flange 18 is spaced apart from the flange 7 by a suitable distance for admitting the wind to blow freely between these parts. The fins 13 carried by 95 the cowl 12 are secured to the flange 18 as well as to the body portion of the cowl, and extend practically from the cylinder 6 to the outermost edges of the flange 18. These fins do not radiate from the center of rotation of the cowl, or in other words, lie in planes not tending to converge upon the shaft portion 15. These planes, if continued, would meet at a point a little distance to the right of the shaft portion 15 100 according to Fig. 3. They are almost but not quite tangential with reference to the surface of the cylinder 6. They are so formed as to gather and concentrate a portion of such atmospheric wind as may 105 chance to blow between the flanges 7, 18, the portion of wind thus affected being di-

rected upwardly so as to pass over the top of the cylinder 6 and laterally away therefrom; the wind thus diverted and concentrated produces, by aspiration, a forced 5 draft within the cylinder 6 and funnel 5 if no draft is already present, and if there be already a draft through the parts in question, such draft is increased.

The operation of my device is as follows:—The parts being assembled and arranged as indicated, if no wind be blowing, the ventilator merely serves as a flue for allowing heated air and gases to pass upwardly and make their escape. If, however, 10 any wind is blowing, a portion of such wind passes between the flanges 7 and 18, and striking the fins 13 is deflected upwardly and concentrated so as to pass over the top of the cylinder 6 and make its escape 15 from the cowl. In doing this it produces, by aspiration, a partial vacuum within the cylinder 6 and funnel 5 constituting the draft member, and in this manner forces a draft within the draft member.

I find in actual practice that by the use 25 of the fins 13 and particularly by forming them as shown and described and mounting them as indicated, the atmospheric wind can be rendered very effective in producing 30 and increasing the draft through the ventilator. I also find that the particular form of cowl herein shown is very effective in preventing wind from blowing downwardly through the draft member. That is to say, 35 if the wind strikes adjacent buildings or other structures and is deflected, it may have a tendency to blow downwardly, but with this form of cowl it is impracticable for the wind to blow downwardly into the draft 40 member to any appreciable extent. The shifting of the cowl to different angles under control of the wind, and the concentrating and directing of portions of the wind so as to carry the same across the top of the 45 draft member, as above described, will, also produce a forward forced draft through the draft member, regardless of the direction in which the wind is blowing.

I claim:

1. A ventilator comprising a draft member, a flange mounted thereupon and having a substantially frusto-conical form, a cowl located adjacent said draft member and provided with a flange of substantially 55 frusto-conical form, said last mentioned

flange being spaced a little distance from said first mentioned flange, and a plurality of fins carried by said cowl and extending therefrom outwardly to the edges of said flange carried by said cowl, said fins diverging from each other for the purpose of deflecting wind relatively to said draft member and thus forcing a draft within said draft member.

2. A ventilator comprising a draft pipe, 65 a frusto-conical flange mounted upon said draft pipe, a cowl supported by said draft pipe and free to move under control of atmospheric wind into different angular positions relatively to said draft pipe, a flange 70 carried by said cowl and having a frusto-conical form, said last mentioned flange being spaced apart from said first mentioned flange, and a pair of fins carried by said cowl and extending outwardly to the edges 75 of said flange carried by said cowl, said fins lying in separate planes which diverge from a point displaced from the axis of rotation of said cowl.

3. A ventilator comprising a draft member, a flange mounted thereupon, a cowl revolvably mounted upon said draft member, a flange carried by said cowl and disposed adjacent to said first mentioned flange so as to facilitate the blowing of wind between 85 said flanges, and a plurality of fins engaging said flange carried by said cowl and lying in divergent planes for the purpose of concentrating a portion of atmospheric wind and directing said portion across said draft 90 member in order to aspirate a quantity of air contained therein.

4. A ventilator comprising a draft pipe, an arch mounted thereupon, a bridge extending across said arch, a stirrup carried 95 by said bridge, a stem engaging said arch and said bridge, a cowl carried by said stem and adapted to be shifted into different positions by the wind, a flange carried by said cowl, a flange carried by said draft 100 pipe, and a plurality of fins carried by said cowl and engaging the flange thereof, said fins diverging for the purpose of controlling currents of atmospheric air in order to cause the latter to aspirate the air contained within 105 said draft pipe.
